WRINGER ROLL STOP MECHANISM

Nicholas L. Etten, Waterloo, Iowa, assignor to
Chamberlain Corporation, Waterloo, IowaApplication June 9, 1934, Serial No. 729,848
Renewed August 17, 1939

3 Claims. (Cl. 68—253)

This invention has reference to wringer roll stop mechanism, particularly to means for controlling rotation of the rolls in accordance with pressure applied therebetween.

The principal object of the invention is to provide a coupling mechanism between the driving element and rolls whereby when pressure is applied between the rolls the coupling is effective to drive the rolls the same being made ineffective when pressure is removed.

Another object is to provide a geared coupling mechanism disposed between the wringer drive element and rolls capable of being forced into geared relationship by means of pressure brought about by conventional wringer roll tensioning means the same being rendered ineffective when the tensioning means is released.

A further object is to provide a geared coupling mechanism comprising a driven element and a co-operative element capable of being forced into or out of geared relationship therewith, the co-operative element being secured to a roll of the wringer whereby when pressure is brought to bear upon the wringer roll, as when the wringer is adjusted to wring clothes, the co-operative element is forced into geared relationship with the driven element to rotate the rolls, and when said pressure is released the co-operative element is made ineffective to maintain the driving connection.

An additional object is to provide coupling means between a wringer drive and rolls, which coupling is effective to drive the rolls only when the rolls are in pressure relation, rotation of the rolls being automatically stopped when said pressure is removed.

Other objects will appear in the following description and accompanying drawings in which:

Fig. 1 is a side elevational view of a wringer embodying my invention, with a portion of the wringer frame broken away to permit clear view of underlying parts;

Fig. 2 is an end elevational view of the same taken from the right of Fig. 1;

Fig. 3 is a fragmental side elevational view of the right hand portion of Fig. 1 showing parts in operated position as will be described;

Fig. 4 is an approximately full size sectional elevational view of my coupling mechanism to be described;

Fig. 5 is a sectional view taken from line 5—5 in Fig. 4 and

Fig. 6 is a plan view taken from line 6—6 in Fig. 1.

Fig. 1 discloses my invention embodied in a

conventional roll wringer generally comprising a lower frame member 10 and frame members 11 and 12, a releasable top frame member 13 carrying a spring 14 supported in the frame by means of an adjustment screw 15.

An upper roll 16 is journaled in the frame in a conventional manner and spring 14 is effective to force it downwardly upon the lower roll 17.

The left hand end of roll 17 is conventionally journaled in frame member 11 and the right hand is supported in a special manner as follows:

Fig. 4 illustrates that the end of drive shaft 18 of the lower roll is fitted with a head member 19 secured to the shaft by means of a pin 20.

15 The head member is provided with indentations or recesses 21 as shown best in Fig. 5.

Indentations or recesses 21 are adapted to be engaged by a series of balls 22 retained in a collar member 23, by means of a cage member 24.

19 The cage is secured in the collar by means of rivets 25.

23 A coupling element 26, adapted to be connected with the driving means of the wringer, is secured in collar 23 and the collar is rotatably supported in a bearing block 27 whereby the collar may be rotated continuously by the power source.

27 Dotted outline in Fig. 4 illustrates that the relative diameters of head 19 and inner periphery of collar 23 are such that head 19 may be moved to a position substantially central of the collar to disable driving engagement between indentations or recesses 21 and balls 22, whereby the head may become a stationary member floating within the continuously rotating collar.

35 Fig. 6 illustrates that frame 12 has inwardly directed edges 12' so proportioned as to confine the head 19 against lateral movement. However, the head is vertically movable between the edges.

40 Referring to the top frame 13, it will be noted that it is retained upon the end frame 11 by means of a hook arrangement 28 which is thought sufficiently well known as to obviate detailed description.

45 The opposite end of the top frame is retained by means of a latch mechanism comprising a member 29 pivotally secured to end frame 12 and having a hook portion 30 adapted to extend over the end of top frame 13 and a reversely fashioned lip 31 at its upper extremity.

50 Hooked with the lip 31 is a complementary hook 32 of a lever 33 which is pivotally supported at 34 upon top frame 13.

55 The lever has an extending end 33' by means of

which it may be manipulated to disengage hook 32 from lip 31.

It will be noted that with the parts in position shown in Fig. 1, the top frame is retained upon the end frames whereby spring 14 may be tensioned by screw 15 to force the upper roll 16 downwardly upon lower roll 17 which in turn forces the indentations or recesses of head member 19 into driving engagement with balls 22 of the rotating collar 23. Obviously a geared coupling is thus formed between the driving elements and lower roll which is effective to rotate the roll so long as the rolls are in pressure relation.

In case lever 33 is manipulated to unhook member 29 the latter will no longer be capable of retaining the top frame and the same will be free to move upwardly to release the tension of spring 14 upon the rolls and the pressure between head 19 and collar 23. The described movements are indicated in dotted lines in Fig. 3.

With spring 14 released the pressure between the head 19 and collar 23 is no longer sufficient to support the geared relationship described, and head 19 is free to assume the central floating position described, into which position it would intermittently be forced by reason of balls 22 alternately engaging and escaping indentation 24, the weight of the rolls not being sufficient to maintain driving relationship therebetween.

It is to be noted that any suitable gear devices may be used in place of the ball-recess arrangement described.

With the foregoing in mind it will be apparent that a wringer embodying my invention has its usefulness and safety factor increased due to immediate arrestment of rotation of the rolls upon release of the roll tensioning means.

What I claim is:

1. A wringer roll drive connecting mechanism comprising, a recessed rotatively driven member, a head member secured to a wringer roll and rotatably disposed in said recess, the interior surface of the recess and exterior surface of said head member being provided with complementary projections and recesses all so proportioned that when said head member is axially aligned with the driven member said projections and recesses are free of engagement, but upon movement of

the head member out of aligned position are engaged whereby rotative movement of the driven member brings about similar movement of the wringer roll.

5. In a roll wringer mechanism having upper, lower and side frame members, a lower roll mounted by one of its ends in a bearing in one side frame member, the roll driving member carried by the opposite side frame member, a driven member secured to said opposite end of said lower roll and loosely supported in said driving member, an upper roll carried between said side frame members and cooperatively engageable with said lower roll, a pressure spring carried by said upper frame member and cooperative with said upper roll for pressing the upper roll into engagement with the lower roll, means for releasing said spring pressure, and complementary indentations and projections on the driving and driven members and co-active with one another to cause the driven member to be rotated by the driving member when the lower roll and its driven member are held downward by said spring pressure, said coactive indentations and projections being so configurated that they are inoperative to effect rotation of said lower roll when said spring pressure is released.

3. In a wringer, a driven roll member and a driving member therefor, one of said members equipped with a hollow cylinder, inwardly projecting rotatable devices mounted in and partially confined in bearings formed in the inner face of the circumferential wall of said cylinder, said devices being equally spaced from each other and from the axis of the cylinder, a shaft rigid with the other member and being of diameter to be rotatable relatively to said cylinder when disposed concentric with the latter, whereby to cause the roll member to remain normally idle, an idle roll associated with said driven roll, spring means manipulable to force said idle roll against said driven roll member to a position eccentric to the driving member, said shaft equipped with recesses in which said rotatable devices engage successively while said shaft is in said eccentric position, thereby driving the latter.

NICHOLAS L. ETTEL.
